DOLLY

Elizabeth E. Kousens, San Diego, Calif., assignor to Peerless Manufacturing Company, El Cajon, Calif., a firm

Application September 9, 1954, Serial No. 32,213

Term of patent 3½ years

(Cl. D14—3)

Figure 1 is a top plan view of a dolly with the handle in folded position showing my new design;

Figure 2 is a side elevational view of the dolly with the handle in extended position;

Figure 3 is a front elevational view of the dolly with the handle in folded position; and

Figure 4 is a perspective view of the dolly with the handle in extended position.

I claim:

The ornamental design for a dolly, substantially as shown.
